UNITED STATES PATENT OFFICE.

FRANK C. HELMICH, OF PHILADELPHIA, PENNSYLVANIA.

SUCTION CLEANING DEVICE.

1,303,059.

Specification of Letters Patent.

Patented May 6, 1919.

Application filed May 11, 1918. Serial No. 234,005.

To all whom it may concern:

Be it known that I, FRANK C. HELMICH, a citizen of the United States, residing at 2233 N. Bancroft street, Philadelphia, in the county of Philadelphia and State of Pennsylvania, have invented new and useful Improvements in Suction Cleaning Devices, of which the following is a specification.

10 An object of the invention is to provide a suction cleaning device of the class also known as vacuum cleaners, for removing particles of dust or dirt or other foreign matter from surfaces, parts of musical instruments, furniture or the like.

The invention more particularly pertains to a device adapted for use in cleaning the tracker bars of musical instruments, such as pianos, and to this end the invention comprehends a simple implement, consisting of few parts that can be cheaply constructed and readily assembled, whereby the accumulated dust or dirt on the tracker bar can be easily sucked therefrom into the implement, and then at any time exhausted from the implement. To this end the implement is designed with a mouth through which the dust is sucked into the implement, and then by a slight adjustment of the implement the dust can be readily discharged from the interior of the implement through the mouth, after the implement has been drawn away from the tracker bar, or part from which the dust has been removed.

35 I am aware that various forms of bellows and suction and discharging devices have been used heretofore for the cleaning of tracker boards of pianos and the like, but in these instances the discharge of the accumulated product is discharged through a separate discharge opening; whereas, in my device I simplify the entire arrangement by discharging the accumulated product from the same opening through which it is sucked into the implement.

40 In the further disclosure of the invention, reference is to be had to the accompanying drawing, constituting a part of this specification, in which similar characters of reference denote corresponding parts in all the views, and in which—

Figure 1 is a vertical sectional view taken through the device.

Fig. 2 is a horizontal sectional view taken 55 on the line 2—2 in Fig. 1.

Fig. 3 is a transverse sectional view taken on the line 3—3 in Fig. 2, and

Fig. 4 is a fragmentary plan view of the implement with parts broken away to disclose the underlying valve structure, the 60 dotted lines indicating one of the valve adjustments.

Referring more particularly to the views, the cleaning device is indicated in its entirety by the numeral 10, and comprehends 65 a bellows frame 11 which is formed by an upper leaf or board 12, and a lower leaf or board 13, connected by a suitable cloth 14 forming the sides and end, the cloth being plaited in an accordion effect. The rear 70 terminals or extremities of the leaves 12 and 13 are reduced to form suitable handles 15, and the front ends of the leaves 12 and 13 are suitably hinged to a block 16 provided with an opening 17 and which forms a part 75 of the bellows for a purpose that will be hereinafter more fully disclosed. The leaves 12 and 13 on their inner faces and adjacent their forward ends are recessed as at 18, to form better connection with the opening 17 80 of the block 16, and hinged on the block 16 is a flap valve 19 engaged by a suitable spring 20, said valve normally closing the inner end of the opening 17, and therefore better termed a closure valve. Attached to 85 the block 16 is a mouth-piece 21 provided with an opening 22, communicating with the opening 17, a bumper pad 23 being secured to the concaved front of the mouth-piece 21, and also provided with an opening 24 90 registering with the opening 22, said bumper being made of a suitable felt or some soft skin, so that in using the implement, the part to which it is applied for the purpose of removing the dust therefrom, 95 will not be injured or scratched.

An exhaust valve 25 of what is generally known as the button-type, is arranged to normally close an opening 26 in one of the leaves, namely, the leaf 13, and said valve 100 includes a pad 27 insuring proper closing of the opening 26, and a stem 28 having connection with the outer end of a spring 29 which is suitably secured to the inner face of the leaf 13. A fender 30 in the nature 105 of a block is secured to the inner face of the leaf 13 to project upwardly a slight distance beyond the normal upward position of the spring 29 so that when the leaf 12 is pressed down it will engage the fender 110.

30 and thereby prevent injury to the
spring 29.

It will be particularly noted by reference
5 to Fig. 1 that the cloth 14 has its back portion,
indicated by the numeral 14^a, arranged
with the edges thereof recessed into grooves
14^b in the leaves 12 and 13, so as to provide
an absolutely air-tight connection at this
point.

10 Referring once more to the pressure valve
19, it will be seen that there is provided an
operating element 31 which is mounted to
turn and to slide in the block 16 and which
is bent at its exterior end to form a handle
15 32, and on the interior end it extends into
the opening 17. The operating element is
formed with a projection 33 that will bear
against the valve 19 and move the same
against the action of the spring 20, when
20 the operating element is rotated in the block.

Now assuming that the operating element
is in normal or inoperative position, as
shown in Fig. 2, and that it is desired to
use the device for the purpose of sucking
25 into the bellows any quantity of dust that
has collected on the tracker bar of a piano,
the mouth-piece is arranged adjacent to the
point of accumulation of the dust and the
bellows then operated by moving the leaves
30 12 and 13 toward and away from each
other. When the leaves are moved toward
each other to compress the bellows, it will
be clear that any air contained therein, when
it reaches a degree of compression greater
35 than the holding action of the spring 29,
will by pressure of the air cause the exhaust
valve 25 to become unseated from the opening
26 and the air will rush out through this
opening, and the bellows can therefore be
40 easily compressed, it being of course under-
stood that no air will pass out through the
mouth-piece because of the valve 19 being
held in closed position by the spring 20 and
by the pressure of air against the valve.
45 Now when the bellows are opened by mov-
ing the leaves 12 and 13 apart, a suction
will be created within the bellows, by rea-
son of the fact that the valve 25 will again
have assumed its normal closing position by
50 the action of the spring 29, so as to effec-
tually close the opening 26, and in order to
fill the bellows with air, the air will have to
pass through the mouth-piece 21, and thus
will be sucked in by the suction created
55 through the opening 22 and the opening 17,
the suction created by opening the bellows
being sufficient to overcome the action of the
spring 20, thus raising the valve 19 to un-
cover one end of the opening 17, and there-
60 by permit the air and accumulated dust to
be sucked into the interior of the bellows.
Now in order to exhaust the air from the
bellows, and have the dust carried out with
the air, after the implement has been re-
65 moved from the tracker bar, the operating

element 31 is rotated from the exterior by
means of the handle 32 thereof, thus caus-
ing the projection 33 to bear against the
pressure valve 19 and force the same against
the action of the spring 20 into an open
70 position, so that the subsequent closing of
the bellows or compression thereof, will per-
mit the accumulated dust and air in the bel-
lows to freely move out through the unre-
stricted openings 17 and 22, so that the
75 accumulated dust and air will pass out
through the mouth-piece 21; it being par-
ticularly noted that in this operation the
valve 25 will not operate, due to the fact
that the air and dust will follow the path of
80 least resistance and pass out through the
opening 17, rather than through the opening
26, which is held closed by the valve 25
and the action of the spring 29.

By repeating this operation, a quantity of
dust can easily be sucked into the bellows
from tracker bars, and then subsequently re-
moved from the same opening or mouth-
piece, and by reference to Figs. 2 and 4 it
will be seen that by sliding the operating
90 element 31 toward the valve 19, or away
from the same, the degree of opening of the
valve 19, when the operating element is
operated to move the projection into en-
gagement with the valve, can be adjusted so
95 that the uncovering of the opening or pas-
sage 17 can be made greater or less as de-
sired, this being particularly desirable
where it is desired to regulate the suction
or projection of the air into or out of the
100 bellows.

In order to prevent large particles from
passing into the bellows and thus destroy-
ing the operativeness thereof, a screen 34 is
disposed between the block 16 and the
105 mouth-piece 21 to traverse the openings 17
and 22, and thereby permit only the finer
particles of dust and dirt, and not large
shavings and the like from entering the bel-
lows when the same are expanded to induce
110 the suction.

From the foregoing description it will be
seen that the device described comprehends
a handy and useful article, that can be oper-
ated by any one not necessarily skilled, and
that the parts being of a simple construc-
115 tion can not readily get out of order, the
device being designed to effectively accom-
plish the purpose for which it is intended.

I claim:

1. A device of the character described, comprising in combination with a bellows, a block provided with a passage and having the bellows connected and hinged thereto, a mouth-piece provided with a passage and attached to the block, the passage of the mouth-piece registering with the passage of the block, a spring-actuated pressure valve normally closing the passage from the block, a spring-actuated exhaust valve normally 125

- closing the passage from the bellows, and an operating element movable from a normal inoperative position to engage with and move the first-mentioned valve in an open 5 position against the action of its spring.
2. A device of the character described, comprising in combination with a bellows, a block provided with a passage and having the bellows connected and hinged thereto, a 10 mouth-piece provided with a passage and attached to the block, the passage of the mouth-piece registering with the passage of the block, a spring-actuated pressure valve normally closing the passage from the block, 15 a spring-actuated exhaust valve normally closing the passage from the bellows, an operating element movable from a normal inoperative position to engage with and move the first-mentioned valve in an open
- position against the action of its spring, and 20 a screen disposed between the block and the mouth-piece and out of the path of movement of said operating element.
3. In a device of the character described, the combination with a bellows and a 25 mouth-piece on the bellows provided with a passage communicating with the interior of the bellows, of a valve normally closing the communication from the mouth-piece to the bellows and vice versa, and an operating 30 element mounted to turn and to slide to engage the valve when the operating element is turned and remove said valve from its normal closing position, and to engage said valve when it is turned and slid to adjust 35 the degree of opening of said valve.

In testimony whereof I affix my signature.
FRANK C. HELMICH.
